United States Patent Office

Des. 229,425

Patented Nov. 27, 1973

229,425

STEREO HEADSET

John P. McCabe, Miller Place, N.Y., assignor to
Instrument Systems Corporation, Jericho, N.Y.

Filed Dec. 27, 1971, Ser. No. 212,846

Term of patent 14 years

Int. Cl. D14—01

U.S. Cl. D26—14 H

FIG. 1

FIG. 2

FIG. 3

FIG. 5

FIG. 4

FIG. 1 is a top plan view of the headset, embodying my new design;

FIG. 2 is a front elevational view of the headset of FIG. 1;

FIG. 3 is a bottom plan view of the headset of FIG. 1;

FIG. 4 is a rear elevational view of the headset of FIG. 3; and

FIG. 5 is a side elevational view of the headset of FIG. 1.

I claim:

The ornamental design for a stereo headset, as shown.
